UNITED STATES PATENT OFFICE

GEORGE S. WRIGHT, OF OTTAWA, ILLINOIS

PUMP CONNECTION

Application filed January 27, 1928. Serial No. 249,811.

This invention relates to improvements in a pump connection and is highly desirable for use in conjunction with a windmill and pump jack, although it is equally adaptable for many and varied uses as will be apparent to one skilled in the art. The invention relates more particularly to means for joining a reciprocatory rod to a plurality of driving elements, the said means permitting the reciprocatory rod to be selectively driven by any of the driving elements and the substitution of one driving element for another while all are in motion.

In the past, various means have been provided for selectively operating a pump by a windmill or a pump jack and for shifting the operation of the pump from one to the other according to the variations in the strength of the wind. These former means, however, have proven more or less objectionable in that in many instances the pump rod could only be operated by the windmill rod under a fairly strong wind, and the operation could not be shifted from the windmill rod to the pump jack, or the opposite, while both were in motion. Moreover, in nearly every case, substitution of a pump jack for the windmill rod or the opposite, as a driving element for the pump rod, was a task exceedingly difficult if not practically impossible for the average woman to accomplish.

The present invention seeks to overcome the above as well as other noted defects and objections in the provision of means for connecting a pump rod to a windmill rod and pump jack, which means are so adapted that either the windmill rod or pump jack may be extremely easily and quickly substituted for the other as a driving element for the pump rod while one or both are in motion.

The invention also seeks to provide adjustable means for joining a pump rod to the windmill rod, whereby the stroke of the pump rod and the leverage thereon may be so adjusted as to be operable by the windmill rod under a very light wind.

Another object of this invention is to provide means for joining a reciprocatory rod to plurality of driving elements whereby the reciprocatory rod may be selectively driven

by either of the driving elements while both are in motion with no resulting damage to any parts of the structure or mechanism.

In many instances it is desirable to drive other mechanisms such as a motor, pulley wheel, etc., or other reciprocating mechanisms, by means of a windmill. Accordingly, it is a further object of the present invention to provide means for connecting a reciprocatory element to a plurality of power take off means, the connection being such that the motion of the reciprocatory element may be selectively applied to the power take off means.

While some of the more salient features, characteristics, and advantages of a device embodying this invention have been above pointed out, others will become apparent from the following disclosures.

The invention includes these and other features of construction and combinations of parts hereinafter described and shown in a preferred form in the drawings, as more particularly indicated by the claims.

In the drawings:

Figure 1 is a fragmentary view in elevation of a windmill, pump and pump jack, equipped with a device embodying features of the present invention.

Figure 2 is a fragmentary view in elevation taken from the left of Figure 1.

Figure 3 is a fragmentary, part sectional and part elevational view, of the connecting means embodying principles of this invention, taken substantially as indicated by line III—III of Figure 2.

Figure 4 is a fragmentary sectional view taken substantially along line IV—IV of Figure 3.

Figure 5 is a fragmentary vertical sectional view taken substantially along the staggered line V—V of Figure 3.

Figure 6 is a fragmentary vertical sectional view taken substantially along line VI—VI of Figure 3.

As shown in the drawings:

In the illustrated embodiment of the present invention there is shown a base 1 upon which is seated a fabricated windmill tower 2, it being understood that the upper-

most portion of the tower is equipped with a vaned rotor and the customary mechanism for actuating a reciprocatory windmill rod 3.

Also mounted on the base 1, is a pump casting 4 having a reciprocatory pump rod 5 projecting therefrom which is maintained in vertical alignment by a suitable guide 6 disposed on one of the transverse members of the tower 2. Of course, the pump rod and other pumping mechanism extends through the base 1 to a suitable water source disposed therebeneath.

In addition to the elements already mentioned, the base 1 acts as a support for a pump jack generally indicated by the reference numeral 7 which comprises, in this instance, a set of bearing brackets 8 in which a crank shaft 9 is journaled on which is mounted a pulley 10. Pivotally secured to the crank shaft 9 is a pitman 11, the upper end of which is connected to the pump rod 5 and the windmill rod 3, as will later appear.

The upper end of the pitman 11 and the lower end of the windmill rod 3, in the present instance, are bifurcated as indicated at 12 and 13, respectively, to receive links 14 and 15, respectively, which are held therein in any desired other manner or as shown by bolts.

Novel means have been provided for adjustably connecting the pitman, pump rod, and windmill rod. These means, in this instance, comprise a cross-bar or lever 16 which is preferably formed of a pair of inverted confronting angle irons 17 held in spaced relationship by floating bushings 18 on the shafts of bolts 19 (Figures 4 and 6) disposed adjacent either end of the lever 16. The links 14 and 15 are apertured at their extremities to receive the floating bushings 18, whereby the windmill rod 3 and the pitman 11 are freely pivotally connected to the lever adjacent opposite ends thereof.

The pump rod 5, in this instance, is preferably flattened along its upper portion as indicated at 20 and extends through the lever 16, being disposed between the angle irons 17. The pump rod carries thereon a clamping element 21 adapted to tightly engage the lever 16 to prevent relative movement therebetween. The clamping member, in this instance, comprises a pair of upright complementary angle irons 22 (Figure 5), the horizontal flanges of which extend inwardly and underlie the outwardly extending flanges on the angle irons 17. The vertical flanges of the angle irons 22 are apertured to receive therethrough the shaft of bolt 23 upon one end of which a hand wheel 24 is threaded. Enclosing the shank of the bolt 23 is an anti-friction bearing sleeve 25 which preferably rests upon the upper surface of the angle irons 17, both the bolt shank, and sleeve passing through an aperture 26 in the flat portion 20 of the pump rod 5. At each end of

the sleeve 25 a lock washer 27 is provided which abuts the sleeve and the adjacent angle iron 22. Obviously, when the hand wheel 24 is tightened upon the bolt 23, the relatively short angle irons 22 will grip the angle irons 17 and prevent relative movement therebetween. When the hand wheel is loosened the clamping action is released, the lock washers 27 aiding in effecting a quick release, and the angle irons 17 or cross-bar 16, may slide through the clamping element.

The operation of the present invention is exceedingly simple and easy to accomplish. Assuming that the pump rod 5 is being driven by the windmill rod 3 and it is desired to substitute the pitman 11 as the driving element, it is only necessary to loosen the hand wheel 24 of the clamping element 21 and slide the lever 16 therethrough to the right as indicated by the dotted lines in Figure 1, and again tighten the hand wheel. When in this position the motion of the pitman 11 will be transferred to the pump rod 5 and the lever 16 will merely pivot at its connection with the windmill rod 3. This exchange of driving elements may be effected while both the pitman and the windmill rod 3 are in motion without injury to any part of the apparatus. The exchange of driving elements in the opposite direction, may of course, be effected by loosening the clamping element and moving the lever 16 to the left as indicated in Figure 1, when the pump rod will be driven by the windmill rod 3 and the lever 16 will merely pivot at its connection with the pitman 11.

It should be noted in connection with the present invention that the lever 16 may be so adjusted as to vary the stroke of the pump rod 5. For instance, assuming that the pump rod 5 is actuated by the windmill rod 3, if the lever 16 is moved to the right (Figure 1), the leverage will be increased and the stroke of the pump rod shortened. The increased leverage, however, permits the pump to be actuated through the windmill mechanism by an exceedingly light wind. Of course, the same adjustments may be effected with relation to the pitman of the pump jack when the windmill is at rest.

In many instances, however, it is desired not only to operate a pump by a windmill, but to operate some other mechanism by a windmill. With the present invention, the windmill rod 3 may be used to drive the pitman 11 through the novel connecting means hereinbefore explained and other driven mechanism may be attached to the pulley wheel 10 or directly to the crank shaft 9, and if the wind is sufficiently strong, the connecting means may be so adjusted that both the pump and pitman 11 may be driven by the windmill rod 3.

From the foregoing it is apparent that I have provided novel connecting means, very desirable for use in connection with wind-

5 mills and pumps operated thereby, and which means may be attached to practically any windmill and pump. The means disclosed herein also permit adjustments of the lever-
age on the pump rod and of the stroke of the pump rod, and are adapted to be very easily adjusted to effect the change of driving elements for the pump rod. Moreover, with the present invention the motion of a driving member 10 may be selectively applied to a plurality of driven members. In addition, the present invention is simple in construction, durable, and economical to manufacture.

15 I am aware that many changes may be made and numerous details of construction may be varied through a wide range without departing from the principles of this invention and I, therefore, do not purpose limiting the patent granted hereon otherwise than
20 necessitated by the prior art.

I claim as my invention:

25 1. In combination, a windmill rod, a pump jack, a pitman connected to said jack, a pump rod, a cross-bar connected adjacent the opposite ends thereof to said windmill rod and said pitman, and means carried by said pump rod and engaging said cross-bar between its ends, said cross-bar being adjustable relative to said means.

30 2. Means for shifting the operation of a pump rod from a windmill rod to a pump jack, said means including a lever pivoted adjacent one end thereof to a windmill rod and adjacent the other end to a pump jack, and means for connecting a pump rod to said lever between the ends thereof, whereby when said lever is driven by either said windmill rod or pump jack it will merely pivot at its connection with the other.

35 40 3. In combination, a windmill rod, a pump jack, a pitman connected to said pump jack, a lever connected to said windmill rod and said pitman, a reciprocatory rod, and clamping means on said rod engaging said lever, said lever being movable relative to said clamping means, whereby said reciprocatory rod may be selectively operated by said windmill rod or said pitman and the operation shifted from one to the other while both are
45 50 in motion.

55 4. Means for connecting a pump rod to a windmill rod and a pitman, said means including a lever, means for pivotally connecting said pitman and said windmill rod to said lever in spaced relationship, and clamping means carried by said pump rod and engageable with said lever between said pivotal connections.

60 5. In combination, a reciprocatory driving element, a lever pivoted adjacent an end thereof to said element, a second reciprocatory driving element pivoted to said lever adjacent the other end thereof, and means for connecting a power take off member to said lever at any point between said driving ele-

ments to be selectively driven by either of said elements.

65 70 6. In combination, a reciprocatory driving element, a lever pivoted to said element, a second reciprocatory driving element pivoted to said lever, power take off means, and means for connecting said power take off means to said lever at any point therealong whereby either of said elements may drive the other or drive said power take off means.

75 80 7. In combination, a pair of reciprocatory elements, a lever pivoted at spaced points therealong to each of said elements, power take off means, and means pivotally associated with said power take off means for connecting the same to said lever at any point therealong, whereby one of said elements may drive the other or drive said power take off means.

85 90 8. In combination, a reciprocatory element, a lever connected thereto, a first power take off means connected to said lever, a second power take off means associated with said lever between said element and said first means, and a connection between said second means and said lever, adjustable to allow longitudinal relative movement therebetween whereby said take off means may be selectively and individually driven by said element, the lever merely pivoting at its connection with the idle take off means.

95 In testimony whereof I have hereunto subscribed by name at Holly, Prowers county, Colorado.
